UNITED STATES PATENT OFFICE

FRANZ HOFMEISTER, OF SCHLEISISCH-OSTRAU, CZECHOSLOVAKIA, AND HANS MELHARDT, OF VIENNA, AUSTRIA, ASSIGNORS TO CHEMISCHE FABRIKEN J. BELLAK, OF VIENNA, AUSTRIA, A FIRM OF AUSTRIA

EVAPORATOR

Application filed December 3, 1928; Serial No. 323,420, and in Austria January 10, 1927.

This invention relates to evaporators, particularly such as are employed for evaporating and concentrating liquids and of the type comprising steam heated tubes, on which the liquid to be concentrated is caused to drizzle down.

In the known apparatus of this kind evaporating tubes of equal diameters are uniformly distributed all over the space of the evaporating chamber through which the liquid has to pass and the liquid drips on them from a distributing device placed at the top of the said chamber. The evaporating surface of the single tubes is constant, while on the other hand the amount of liquid drizzling down on them is varying, as the liquid on the way down is progressively concentrated. If for instance the liquid ought to be concentrated in the evaporator to a quarter of its initial quantity or volume, only a quarter of the quantity of liquid delivered to the highest horizontal layer of tubes will arrive at the lowest row. Under these circumstances the evaporating capacity of the tubes is not completely utilized for the reason, that the lowest tubes receive considerably less liquid than they should be capable of vaporizing, while, on the other hand, the liquid coming in contact with the tubes of the highest horizontal row exceeds the effective range of the latter.

An object of our present invention is to do away with this drawback and to provide an arrangement, by which the vaporizing capacity of all the tubes is uniformly utilized to its full extent which arrangement can of course only consist in that the heating surface successively reached by a determined initial and successively decreasing amount of liquid decreases from top to bottom. Such decrease can of course be effected in any manner preferred by the expert constructor, for instance in such manner, that the number of tubes of one single horizontal tube row decreases from the highest row downward.

A feature of the known arrangements of the evaporating tubes consists in this, that the tubes of one horizontal layer are in staggered relation with respect to the pipes of adjacent layers, that is to say of the one

above and the one underneath it. The intended effect of this known arrangement is to obtain, that the liquid spattering off from one pipe is caught up by the staggered pipes of the following layer, but in fact this result is realized only in the upper layers of tubes, where the amount of liquid attaining each tube is relatively large. At the lower layers much less liquid arrives, the quantity being so little, that the entire liquid arriving there is held on the surface of the tube by adhesion in form of a thin film and no drizzling takes place any more. Consequently of the lowest layer every second tube receives nearly no liquid at all.

Also this inconvenience is in the apparatus according to our invention avoided by a special arrangement of the pipes.

Further objects and advantages of our apparatus will be set forth with reference to the drawings, in which, by way of example, an embodiment of our invention is illustrated.

Fig. 1 shows a front elevation of an evaporator comprising several evaporating chambers or elements, the front wall of the middle element being taken off.

Fig. 2 a side view of an element, partly sectional,

Fig. 3 a plan view of the entire apparatus,

Fig. 4 a sectional view of the feeding device and of an evaporating tube at an enlarged scale,

Fig. 5 a section through the feeding device by the line V—V of Fig. 4,

Fig. 6 a sectional view according to line 6—6 of Fig. 4,

Fig. 7 a sectional view of a collecting vessel (receiver) and

Fig. 8 a modified form of the latter.

In the case as shown, the entire apparatus comprises three evaporating elements 1, 2, 3 constructed all alike. 4 indicates the evaporating chamber properly spoken, which for manufacturing conveniences is made of several parts or sections. In the evaporating chamber the heating tubes 5 are placed, which extend through the front wall 6 and the rear wall 7 of the element. In each horizontal row of tubes of the upper section there are four tubes, in each row of the middle sec-

tion two tubes and in the lower section there is only one vertical row of tubes. The heating tubes are arranged vertically above each other and are in both walls mounted so as to be easily interchangeable.

To the front end of each tube a socket 8 is secured by welding and at the rear end a cap 9 is put on under tightening pressure. Between a flange 10 of the socket 8 and a tapered edge of the opening 11 provided in the front wall 6 an annular gasket 12 is interposed, the tightening of which is obtained by pressing the socket 8 against the wall 6 by means of arms 13 engaging with a second flange of the socket. The arms 13 turn on screw-bolts 14 and can be pressed against the outer flange of the socket by the screw nuts 15.

The front end of the socket contains a four armed cross 16 into the boss of which a bolt 17 is screwed carrying a valve 18, by which the ingress opening of the socket can be throttled to any convenient extent by adjusting the position of the bolt 17 accordingly.

The cap 9 at the rear end of each tube is tightened by an annular gasket 19 and provided in its highest part with an outlet 20 for the escape of noncondensable gases and vapors and on its lowest part with an outlet 21 for the water resulting from condensation. The sectional area of the outlet 20 can be varied by means of the adjustable valve 22 and that of the outlet 21 by a turning slide valve 23, the window 24 of which is brought to coincide more or less with the opening 21. The means for keeping the cap 9 in tightening position are not shown. They may be the same as used for keeping the socket 8 in tightening position.

Between the last tubes of one group or section having the same number of tubes in one horizontal row and the highest tubes of the next group a collecting vessel 25 (Fig. 7) or 26 (Fig. 8) is inserted, which collects the liquid drizzling down from two or more vertical tube rows and lets it run down on a vertical row of tubes beneath it. These collecting vessels have the form of pans, the bottom of which has a slotlike outlet 27 extending parallel to the tubes 5. The front and rear walls of these collecting pans are provided with circular holes which permit the pans to be simply hung up on the tubes by shifting them thereon. Thus the pans may, as is shown in the middle section of the middle element of Fig. 1 be placed higher or lower as required.

Above the highest horizontal row of tubes the feeding device is placed. It consists of tubes 28 arranged parallel to the evaporating tubes, each of the latter being provided with a longitudinal slot 29, in which a rail or bar 30 of double wedged section is placed. The liquid when flowing out from the slot 29 runs along the tapered sides of the bar 30 and from the lower edge of the latter falls

down in the form of a thin layer or film of liquid. For regulating the quantity of the liquid to be delivered to the evaporating tubes the position of the wedged bar 30 is adjustable in vertical direction, the adjustment being effected by turning a shaft 31, on the eccentric part 32 of which an arm 33 is pending. To the bolt 34 of this arm a fork 35 is connected, which carries the bar 30 and by means of the shaft 31 and the tube 28 is guided so as to move in a straight way only.

The tubes 28 are closed on one end and on the other branching off from transversal tubes 36, which are fed from a manifold or supply pipe common to all elements.

Adjacent to the walls 6 and 7 of the evaporation chamber there are chambers 37 and 38, the tubes 5 communicating at their front ends with the chamber 37 and at their rear end with the chamber 38. From the chamber 37 steam is supplied into the tubes 5. The chamber 37 of the first element communicates by a pipe 39 with the main pipe supplying the live steam, the chamber 37 of the second element by a pipe 40 with the evaporating chamber of the first element, the chamber 37 of the third element by a pipe 41 with the evaporating chamber of the second element. To the evaporating chamber of the third element a condenser is connected by means of a pipe 42. To the upper part of the chambers 38 of all elements a suction duct is connected for sucking off the noncondensable gases and vapors and to their lower part a pipe, in which the water resulting from condensation is collected. From the bottom of each evaporating element a duct 43 leads to a receptacle 44, from which the concentrated liquid is drawn off at intervals.

When the apparatus is operated, the same amount of liquid to be concentrated flows to the tubes 28 of all three elements. In the first element the evaporation is effected by the live steam passing through the tubes 5, in the second element by the vapors coming from the evaporation chamber of the first element and in the third element by the vapors escaping from the evaporating chamber of the second element. As the pressure decreases within the evaporating chambers of the consecutive elements, the evaporation in the subsequent elements sets in at lower temperatures, so that the total amount of heat to be imparted to the liquid under treatment is less than in the case of the elements being connected in series with respect of the supply of liquid to each element. Under these conditions also the height of the entire apparatus is smaller than if the elements were connected in series and placed one on top of the other.

The non-condensable gases and vapors are continuously drawn off from the evaporating tubes through the openings 20, which procedure is of essential influence on the utiliza-

tion of the heating surface of the tubes. Also the fact, that the condensate and the vapors are flowing in the same direction, is of importance for obtaining high efficiency.

5 The sectional area of the opening 21, through which the condensate escapes, is adjusted so, that the opening is permanently closed by the water, whereby the escape of noncondensed vapor is obviated.

10 As in addition thereto, owing to the special arrangement of the evaporating tubes, each tube comes in contact with such an amount of liquid only, which is adjusted so as to suit its vaporizing capacity, a perfect 15 utilization of the heat is thus realized.

15 If in operating the apparatus it should occur, that the evaporation at the place where the collecting pan 25 is put, has not proceeded to such degree as required, and if this can- 20 not be remedied by adjusting the valves 18 on the evaporating tubes nor by altering the position of the wedged bars 30 on the supply pipes the collecting pan 25 must be placed deeper for example in the position 25'.

25 What we claim is:

1. An evaporator with steam heated tubes, on which the liquid to be concentrated is drizzling, in which evaporator the heating surface reached by a determined initial and 30 successively decreasing amount of liquid is decreasing from top to bottom.

2. An evaporator with steam heated tubes of equal diameter, on which the liquid to be concentrated is drizzling, in which evaporator horizontal rows of tubes containing each equal numbers thereof are united to 35 form groups and the number of tubes in the horizontal rows of each group is decreasing from the top to the bottom.

40 3. An evaporator comprising steam heated tubes drizzled on by the liquid to be concentrated and arranged in horizontal rows, the tube number of which rows decreases by groups from the top downward, and collect- 45 ing receptacles placed between adjacent groups, which receptacles are adapted to take up the liquid drizzling off from several vertical rows of tubes and to lead it through an outlet to a vertical row of tubes.

50 4. An evaporator comprising steam heated tubes drizzled on by the liquid to be concentrated and arranged in horizontal rows, the tube number of which rows decreases by groups from the top downward, and collect- 55 ing receptacles placed between adjacent groups, which receptacles are adapted to take up the liquid drizzling off from several vertical rows of tubes and to lead it through an outlet provided in their bottom 60 to a vertical row of tubes.

5. In an evaporator the combination of an evaporating chamber traversed by tubes, in the upper part of which chamber means for distributing the liquid to be concentrated are 65 provided, steam admission chambers, with

which the evaporating tubes are communicating at their front ends, and of vacuum chambers communicating with the evaporating tubes at their rear end, each of which rear ends is in its upper part provided with an outlet for the noncondensable gases and vapors and on its lower part with an outlet for the water resulting from condensation.

In testimony whereof we have signed our names to this specification.

FRANZ HOFMEISTER.
HANS MELHARDT.
